A. FRANKEL.

SNAP FASTENER.

APPLICATION FILED NOV. 26, 1920.

1,391,250.

Patented Sept. 20, 1921.

INVENTOR

Adolph Frankel.

BY HIS ATTORNEY

R. E. Bourne

UNITED STATES PATENT OFFICE.

ADOLPH FRANKEL, OF NEW YORK, N. Y.

SNAP-FASTENER.

1,391,250.

Specification of Letters Patent. Patented Sept. 20, 1921.

Application filed November 26, 1920. Serial No. 426,389.

To all whom it may concern:

Be it known that I, ADOLPH FRANKEL, a citizen of the United States, and resident of New York city, borough of Manhattan, in the county of New York and State of New York, have invented certain new and useful Improvements in Snap-Fasteners, of which the following is a specification.

My invention relates to the class of fasteners commonly called "glove fasteners" and "snap fasteners."

The object of my invention is to provide a fastener that will be simple and cheap in construction, effective in use, and the members of which may be readily attached to the goods to be fastened, the construction provided enabling the complementary members to be quickly attached to the goods by suitable machinery.

My invention comprises novel details of improvement that will be more fully herein-after set forth, and then pointed out in the claims.

Reference is to be had to the accompanying drawings forming part hereof, wherein

Figure 1 is a face view of the male member of the fastener; Fig. 1^a is a reverse view of Fig. 1; Fig. 2 is a section on line 2, 2 in Fig. 1; Fig. 3 is an inside face view of the female member of the fastener; Fig. 4 is a section on line 4, 4 in Fig. 3; Figs. 5 and 6 are enlarged sections respectively on the lines 5, 5 and 6, 6 of Fig. 4; Fig. 7 is a sectional view, on an exaggerated scale, of the members of the fasteners assembled.

Similar numerals of reference indicate corresponding parts in the several views.

The numeral 1 indicates the male member of the fastener shown comprising a flat plate having a projection or button 2, which may be formed integral with or fastened to said plate in any suitable manner. Projection 2 is shown nearly spherical in shape having the reduced or neck-like part 2^a to receive the retaining springs of the female member of the fastener. The member 1 is shown provided with holes or slots 3 on opposite sides of projection 2 to receive prongs 4 extending from a retaining plate 5. The prongs 4 may be struck-out from the metal of retainer plate 5 to pass through the goods 6 and through the holes 3 in member 1 to be clenched over the latter when member 1 and retainer plate 5 are placed on opposite sides of the goods (Fig. 2). The member 1 and retainer 5 are shown in relatively narrow

elongated form which may be made cheaply of sheet metal.

The female member 7 of the fastener has a central raised portion 7^a and laterally extending base portions 7^b to fit against the goods 8. The raised portion 7^a is provided with a hollow extension 7^c projecting in the direction of the plane of base portions 7^b and between the latter, adapted to receive the male projection or button 2 (Fig. 7). The member 7 may be cheaply made of relatively narrow elongated sheet metal, the parts 7^a, 7^c being struck-out of the metal in such relation that the cup-like part 7^c opposes the goods without protruding thereon. Springs 9 are secured to the raised wall 7^d of member 7 to engage and retain male projection or button 2. The free ends 9^a of said springs project through slots 10 in the opposite sides of part 7^c of member 7 to enter the reduced part 2^a of projection 2 when the latter is in part 7^c to retain said parts together (Fig. 7). The outer ends of springs 9 are shown secured to wall 7^d by loop-like ears 11 struck-out from said wall on opposite sides of cup-part 7^c, said ends of said springs being pushed into said ears to be clamped by the latter. Said springs are shown substantially in U-shape whereby their free ends are resilient for engaging projection 2 and to permit ready release of the latter. The ears and springs are on the same side of wall 7^d.

The base portions 7^b of member 7 are shown provided with holes or slots 12 to receive prongs 13 that project from retaining plate 14 through the goods 8. The retainer 14 is shown in relatively narrow elongated form corresponding to member 7, the retainer and its prongs securely retaining said member on the goods when said parts are assembled as in Fig. 4.

When the complementary members 1 and 7 are secured upon the goods 6 and 8 the projection 2 may be readily pushed into the cup 7^c to be retained by the springs 9, and said members may be readily separated. The construction of the parts is such that the male and female members may be readily assembled on the respective goods 6 and 8 either manually, or by suitable mechanism, whereby the prongs of the retainers may be pushed through the goods and through the holes or slots in the complementary members and clenched on the latter, the retainers providing bearing along the goods to firmly re-

sist strains from the members. While I prefer two springs 9, one or more such springs may be used on member 7.

Having now described my invention, what

5 I claim is:

- 10 1. A fastener comprising complementary members, one of said members having a projection, the other member having a base and a raised portion provided with a hollow extension to receive said projection, said extension projecting toward the plane of the base, and a spring on the second named member extending into a slot in the side of said extension to engage said projection therein, said base extending outwardly on opposite sides of said raised portion and provided with openings beyond the latter, and a retainer having prongs to enter said openings to clamp on the base.
- 15 2. A fastener member having a base portion and a portion raised therefrom and provided with a hollow extension projecting toward the plane of the base and having a slot, said member having an ear and a spring carried by the ear and extending into said slot, said base projecting laterally from the raised portion and provided with openings beyond the raised portion.
- 20 3. A fastener member having a base portion and an intermediate raised portion having an outer wall, a hollow extension from said wall provided with a side slot, a spring entering said slot, and an ear integral with said wall receiving a portion of said spring to hold it with relation to said extension.

4. A snap fastener comprising complementary members, one of said members comprising an elongated plate having a button-like projection, the other member having a base and a raised portion provided with an outer wall spaced from the base, said wall having a hollow extension projecting toward the plane of the base and provided with a side slot, said wall having an ear, and a spring having one portion secured in said ear and another portion located in said slot to engage said projection.

5. A snap fastener comprising complementary members, one of said members comprising an elongated plate having a button-like projection, the other member having a base and a raised portion provided with an outer wall spaced from the base, said wall having a hollow extension projecting toward the plane of the base and provided with a side slot, said wall having an ear, and a spring having one portion secured in said ear and another portion located in said slot to engage said projection, the first named member having slots on opposite sides of said projection, a plate having prongs to enter said slots, the base of the second named member having slots on opposite sides of said projection, and a retainer plate having prongs to enter said slots.

Signed at New York City, in the county of New York, and State of New York, this 24th day of November, A. D. 1920.

ADOLPH FRANKEL.
